DESIGN FOR A HAND MIRROR

Belle Kogan, New York, N. Y., assignor to Celluloid Corporation, a corporation of New Jersey

Application May 24, 1935, Serial No. 56,992

Term of patent 7 years

To all whom it may concern:

Be it known that I, Belle Kogan, a citizen of the United States, residing at New York, county and State of New York, have invented a new, original, and ornamental Design for Hand Mirrors, of which the following is a specification, reference being had to the accompanying drawing, forming a part thereof.

In the accompanying drawing:

Fig. 1 is a front view of a hand mirror showing my design; and

Fig. 2 is a view of the back of the mirror shown in Fig. 1.

In the drawing the horizontal lines have been used merely for shading effects and do not constitute a part of the design. The back side of the handle where it is joined to the mirror frame is designed to simulate a buckle.

I claim:

The ornamental design for a hand mirror or similar article, substantially as shown and described.

In testimony whereof, I have hereunto subscribed my name.

BELLE KOGAN.
